UNITED STATES PATENT OFFICE.

HENRY R. TUCKER, OF BALBOA, CANAL ZONE, ASSIGNOR OF ONE-HALF TO JOHN G. CLAYBOURN, OF PEDRO MIGUEL, CANAL ZONE.

GOLD-COLLECTING CUP.

Application filed November 20, 1926, Serial No. 149,698, and in Panama October 9, 1926.

The present invention is concerned with the provision of an apparatus for recovering the gold in beach sand by the action of the tide.

5 An object of the invention is to provide a collection receptacle so constructed that it may be placed on the beach between the high and low tide lines, and the sand washing over the receptacle under the influence of the wa-

10 ter will give up its deposit of gold.

In a preferred embodiment of the invention, the device is in the nature of a cup-like receptacle embedded in concrete or some other firm foundation and partially filled 15 with mercury or equivalent material. The specific gravity of the mercury prevents the sand from sinking therein, while permitting the gold particles to settle to the bottom. The mercury is too heavy to be washed out 20 of the cup by the ordinary action of the water and sand rushing over it, and means is provided for preventing the mercury from being dislodged by the pounding action of the breakers.

25 More general objects of the invention are to provide a gold recovery apparatus of this nature of simple, practical, construction, which will result in the recovery of gold at no labor cost, which will be rugged, durable and efficient in use, and which is well suited to the requirements of economical manufacture and convenient installation on the beach.

With the above noted and other objects in 35 view, the invention consists in certain novel features of construction and combinations and arrangements of parts, as will be more fully hereinafter set forth and pointed out in the claims. The invention may be more 40 fully understood from the following description in connection with the accompanying drawings, wherein—

Fig. 1 is a vertical sectional view through 45 an apparatus embodying the present invention, showing the same in applied position.

Fig. 2 is a perspective view of the protective baffle.

Fig. 3 is a perspective view of the cup with the baffle removed.

50 It is to be understood at the outset that the device of the present invention, which I prefer to term "a beach cup gold collector", may have a wide range of utility in other types of gold recovery processes.

In the drawings I have designated at 10 a 55 sand beach, and at 11 a concrete block embedded in the beach and flush with the surface thereof at some point between the high and low tide lines. Preferably the block is disposed at about the mean tide line in order 60 that the action of the tides may be taken advantage of for the greatest possible length of time.

Embedded in the block, is a receptacle designated generally at 12 which includes an 65 annular trough 13 and a central post 14, the upper end 15 of which projects well above the trough and is tapered for the reception of a disc-like baffle member 16 seating on a shoulder 14a of the post.

70 The central bore of the baffle 16 is tapered at 17 in conformity with the shape of the upper end 15 of the post. The baffle member projects laterally beyond the outer edges of the trough 13, so that the mercury 18 which partially fills the trough is protected 75 from the direct downward pounding action of the surf, and there is no danger of the mercury being splashed out of the trough or cup by the sudden impact of a body of descending water.

80 The operation of the device is substantially as follows. The water washing over the face of the block 11 carries a certain amount of sand over the trough 13. This sand is not heavy enough to sink in the mercury 18, but any minute gold particles carried with the sand will be deposited in the mercury and sink to the bottom thereof. The upper portion of the trough will be at 85 all times filled with a floating layer of sand, or water, or both, but the presence of this layer will in no way affect the efficiency of the apparatus, since when the water rushes over it, the sand will be constantly washed 90 out and replaced.

95 The mercury is so heavy that the ordinary washing action of the water passing over it cannot dislodge it, and the baffle member effectively prevents splashing of the mercury by the direct downward thrust thereon which might be caused by the breaker.

100 Obviously various changes and alterations might be made in the general form and arrangement of parts described without departing from the invention. Hence I do not wish to limit myself to the details set forth, but shall consider myself at liberty to make 105

such changes and alterations as fairly fall within the spirit and scope of the appended claims.

I claim:

- 5 1. A gold recovery apparatus adapted for disposition on a beach between high and low tide lines, including an open receptacle adapted to be partially filled with mercury and a guard for protecting the mercury from the direct downward impact of breaking waves and means for anchoring the receptacle with its open end approximately flush with the surface of the beach.
- 10 2. A gold recovery apparatus adapted for disposition on a beach between high and low tide lines, including an open receptacle adapted to be partially filled with mercury and a guard for protecting the mercury from the direct downward impact of breaking waves and means for anchoring the receptacle with its open end approximately flush with the surface of the beach, said guard being disposed far enough above the receptacle to permit the shifting sand to be washed back and forth over the mercury.
- 15 3. A gold recovery apparatus adapted for disposition on a sand beach between high and low tide lines including an anchoring block embedded in and approximately flush with the beach, an open mercury cup embedded in the block, and approximately flush with the surface thereof, and a guard to prevent the breaking waves from dislodging the mercury.
- 20 4. A gold recovery apparatus adapted for disposition on a sand beach between high and low tide lines including an anchoring block embedded in and approximately flush with the beach, an open mercury cup embedded in the block, and approximately flush with the surface thereof, a guard to prevent the breaking waves from dislodging the mercury, said cup including a central guard supporting post and a mercury-receiving trough around the post.
- 25 5. A gold recovery apparatus adapted for disposition on a sand beach between high and low tide lines including an anchoring block embedded in and approximately flush with the beach, an open mercury cup embedded in the block and approximately flush with the surface thereof, a guard to prevent the breaking waves from dislodging the mercury, said cup including a central guard supporting post and a mercury-receiving trough around the post, the guard comprising a disc seated on the post and extending laterally above the trough beyond the outer edge thereof.
- 30 6. A gold recovery apparatus adapted for disposition on a sand beach between high and low tide lines including an anchoring block embedded in and approximately flush with the beach, an open mercury cup embedded in the block, and approximately flush with the surface thereof, a guard to prevent the breaking waves from dislodging the mercury, said cup including a central guard supporting post and a mercury-receiving trough around the post, the guard comprising a disc seated on the post and extending laterally above the trough beyond the outer edge thereof, said post including a tapered upper end fitting a tapered opening in the guard disc.
- 35 7. A gold recovery apparatus adapted for disposition on a sand beach between high and low tide lines including an anchoring block embedded in and approximately flush with the beach, an open mercury cup embedded in the block, and approximately flush with the surface thereof, a guard to prevent the breaking waves from dislodging the mercury, said cup including a central guard supporting post and a mercury-receiving trough around the post, the guard comprising a disc seated on the post and extending laterally above the trough beyond the outer edge thereof, said post including a tapered upper end fitting a tapered opening in the guard disc, and a shoulder on which the guard disc seats.

HENRY RONELCER TUCKER.
